UNITED STATES PATENT OFFICE.

ROBERT C. SCHIEMMEL, OF UNION CITY, INDIANA.

DESIGN FOR A VEHICLE-CUSHION.

SPECIFICATION forming part of Design No. 24,307, dated May 14, 1895.

Application filed November 28, 1894. Serial No. 530,291. Term of patent 7 years.

To all whom it may concern:

Be it known that I, ROBERT C. SCHIEMMEL, a citizen of the United States, residing at Union City, in the county of Randolph and State of Indiana, have invented and produced a new and original Design called a Cushion for Vehicles, of which the following is a specification, reference being had to the accompanying drawing, showing a part thereof.

10 The leading feature of the design is a vehicle cushion, the surface of which is composed of a series of tapering convolutions resembling in shape in section the halves of cylinders or cones, forming radiating lines

15 between the said convolutions or semi-rolls in which are located ornamental cords giving the cushion a very ornamental appearance.

In the accompanying drawing the figure represents a buggy cushion formed according to my invention.

In the said drawing the reference numeral 1 designates the cushion; 2, the convolutions or tapering semi-rolls; 3, the radiating lines between said convolutions, and 4, the ornamental cords seated between said convolutions.

What I claim is—

The design for a vehicle cushion substantially as shown and described.

ROBERT C. SCHIEMMEL.
